UNITED STATES PATENT OFFICE.

CHARLES R. ALLEN, OF ASHTABULA, OHIO, ASSIGNOR TO THE ASHTABULA BOW SOCKET COMPANY, OF ASHTABULA, OHIO, A CORPORATION OF OHIO.

VEHICLE-TOP.

1,379,893.

Specification of Letters Patent. Patented May 31, 1921.

Application filed January 15, 1915. Serial No. 2,363.

To all whom it may concern:

Be it known that I, CHARLES R. ALLEN, a citizen of the United States, and a resident of Ashtabula, county of Ashtabula, 5 and State of Ohio, have invented a new and useful Improvement in Vehicle-Tops, of which the following is a specification, the principle of the invention being herein explained and the best mode in which I have 10 contemplated applying that principle, so as to distinguish it from other inventions.

The present invention consists, in effect, of certain improvements in the construction of the "one man top" which forms the 15 subject matter of my co-pending application filed May 9, 1914, Serial No. 837,356. The term "one man top" is used here, as in such other application and in the art in general, to designate a top for a two-seated 20 vehicle that is wholly supported from the rear bows, so that it is not necessary to have two persons, one on each side, to manipulate the top in either raising or closing the same, as is the case where forward bows 25 are used, which require to be attached to the front seat when the top is being raised, or detached therefrom and carried back and secured to the rear bows when the top is to be folded. The object of the present invention is to further simplify the construction 30 of tops of this sort, as well as to provide means whereby the folding operation is facilitated; also to provide an improved device for securing the front end of the top 35 to the wind-shield, which forms the usual point of attachment for such end to the body of the vehicle. To the accomplishment of the foregoing and related ends, the invention, then, consists of the means herein- 40 after fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:—

Figure 1 is a side elevational view of the 50 bows forming the top-supporting structure embodying the present improvements; Fig. 2 is a view similar to Fig. 1, but showing a modification in construction; and Fig. 3 is a sectional detail on a larger scale.

As in the construction of top shown in

my co-pending application above referred to, I utilize in the framework of the present improved top a forward main bow 1 pivotally attached to the body 2 of the vehicle adjacent the rear seat, together with a rear main bow 3, which is preferably pivotally attached to such forward main bow. In addition, a supplemental bow 4 may be provided between the two main bows if desired, being shown for illustrative purposes in Fig. 2 as pivotally attached to said rear main bow 3.

The portion of the structure of present interest is the forwardly extending frame whereby that portion of the top covering 5, 70 which projects over the front seat, is supported. This structure comprises, as before, an articulated auxiliary bow, or, as it is sometimes called, outrigger bow 6, the latter term applying more especially to the 75 outer portion or bow 7 proper which is secured to the forward main bow 1 by means of arms 8 pivotally attached to the latter and to the rear ends of such outrigger bow, and so constituting the inner 80 portion of said articulated auxiliary bow 6. The rear ends of this outer portion 7 of the auxiliary bow, or in other words the rear ends of the outrigger bow, proper, curve upwardly so that an angle is formed on the 85 lower side of said bow with the inner portion of the auxiliary bow formed by arms 8, thereby causing the longitudinally rearward thrust of the outrigger bow, when the top is raised and such bow extended in a 90 substantially horizontal direction, to tend to raise said arms 8 upwardly about their points of pivotal attachment to the forward main bow 1.

Pivotally attached to arms 8, is a second 95 supplemental bow 9, which, in the extended position of the top, is designed to lie parallel with such arms so as to support the top covering 5 at a point intermediate between the forward main bow 1 and the outrigger bow 7. This supplemental bow 9 is preferably fitted with lugs or clips 10, that are adapted to insure interlocking engagement between such bow and the arms 8 in the position of parts just referred to.

In the extended condition of the top, in which, as already indicated, the outrigger bow 7 projects substantially horizontally over the front seat of the vehicle, the outer end of such bow is designed to be tempo- 110

22

rarily secured to the vehicle body, preferably through the medium of the wind-
shield frame 11 which, in modern cars, is a
more or less rigid structure permanently at-
tached to the dash or cowl 12. While short
straps, with or without snaps or like means,
are ordinarily employed to secure the for-
ward end of such outrigger bow to the wind-
shield frame, I preferably utilize two hooks
13 of the sort illustrated in detail in Fig. 3
for this purpose, one such hook being pivot-
ally attached to each side of the bow 7 just
back of its front end and on the inside, and
being adapted to engage a pin 14 on the ad-
jacent side of the wind-shield frame. The
pins 14 are fitted with winged nuts 15 by
means of which the hooks may obviously be
clamped securely to the frame and the front
end of the outrigger bow thus held in more
or less close relation to the upper edge of
the latter. When the top is to be folded
back out of the way each hook is swung back
parallel with the corresponding side of the
bow 7 where it may be secured by means
of a second pin 16 with a winged nut 17
similar to the one on the wind-shield frame.
Since it is desirable that the forward
main bow 1 be folded back simultaneously
with the folding of the articulated auxiliary
bow 6, links 20 may be provided, as shown
in Fig. 1, to connect such forward main bow
with the supplemental bow 9, such links
preferably having a loose connection with
either the main bow or such supplemental
bow as shown, so as not to interfere with the
stretching of the top covering 5 when the
top is being extended, since they have noth-
ing to do with the support of the forwardly
extending structure. However, when the
hooks 13 for securing the forward end of
the outrigger bow to the vehicle body are
detached from the pins 14, and such outrig-
ger bow folded up by depressing the joint
connecting the same with the rear portion
of the auxiliary bow consisting of the arms
8 in the direction indicated by the arrow
in Fig. 1, the supplemental bow 9 will si-
multaneously be moved into a more or less
vertical position, and this will have the ef-
fect of tilting said forward main bow 1
rearwardly, thus folding the same onto the
rear main bow 3. In this way all the bows
are simultaneously forced toward each
other. In addition to links 20 thus con-
necting the supplemental bow 9 with the
forward main bow 1, a second pair of links
21 connecting said supplemental bow with
the respective sides of the outrigger bow 7
may be utilized, as shown in Fig. 2. These
additional links 21 will insure the backward
tilting of said supplemental bow when the
hinge joint between the outrigger portion
and rear portion of the articulated auxil-
iary bow is depressed.
65 In both of the foregoing constructions,

the several bows fold up very compactly
when the top is closed and project rear-
wardly from the point of attachment of the
main bows to the vehicle, as indicated in
dotted outline in Fig. 1. In both such con-
structions, moreover, by reason of the inter-
engagement between the rear portion of the
articulated auxiliary bow with the supple-
mental bow 9, a truss frame is in effect
formed, when the outer end of the outrigger 75
portion of such bow is drawn downwardly
so as to put the top covering under tension.
The arrangement of the links, and particu-
larly of link 20 connecting the forward main
bow with the supplemental bow 9 carried 80
by the arms 8 forming the rear portion of
the articulated auxiliary bow, insures the
simultaneous collapsing of the several sec-
tions of the top by causing all of the bows
to tilt or fold backwardly upon each other, 85
as soon as the joint in the auxiliary bow is
broken or bent downwardly. The use of
hooks 13 such as those shown and described
for securing the forward end of the outrig-
ger bow to the wind-shield frame, has the 90
advantage over the straps and other devices
heretofore used, in that the top is held
against vibration vertically while still be-
ing allowed a certain amount of play in a
longitudinal, that is in a horizontal direc- 95
tion. Said hooks may furthermore be dis-
posed entirely out of the way when not in
use, as when the top is folded.

Other modes of applying the principle of
my invention may be employed instead of 100
the one explained, change being made as re-
gards the mechanism herein disclosed, pro-
vided the means stated by any of the fol-
lowing claims or the equivalent of such
stated means be employed.

I therefore particularly point out and dis-
tinctly claim as my invention:—

1. In a vehicle top, the combination of a
main bow suitably attached to the vehicle
body; an articulated auxiliary bow pivot- 110
ally attached to said main bow; a supple-
mental bow pivotally attached to the inner
portion of said auxiliary bow and adapted
to interengage therewith in the raised posi-
tion of the top; and a link connecting said 115
supplemental bow with said main bow, said
link having a lost-motion connection with
one of said bows.

2. In a vehicle top, the combination of a
main bow suitably attached to the vehicle 120
body; an articulated auxiliary bow pivot-
ally attached to said main bow; a supple-
mental bow pivotally attached to the inner
portion of said auxiliary bow and adapted
to interengage therewith in the raised po- 125
sition of the top; and links connecting said
supplemental bow with said main bow and
with the outer portion of said auxiliary bow,
respectively, said links having a lost-motion
connection with said bows.

3. In a vehicle top, the combination of a main bow suitably attached to the vehicle body; an articulated auxiliary bow pivotally attached to said main bow; a supplemental bow pivotally attached to the inner portion of said auxiliary bow and adapted to interengage therewith in the raised position of the top; links connecting said supplemental bow with said main bow and having lost motion connection with the former;
- 5
- 10

and other links connecting said supplemental bow and said auxiliary bow and having lost motion connection with the latter.

Signed by me, this 11th day of January, 1915.

CHARLES R. ALLEN.
